UNITED STATES PATENT OFFICE.

EMMA K. DORER, OF NEW YORK, N. Y.

EDUCATIONAL GAME.

1,210,614.

Specification of Letters Patent.

Patented Jan. 2, 1917.

Application filed July 27, 1916. Serial No. 111,736.

To all whom it may concern:

Be it known that I, EMMA K. DORER, a citizen of the United States, residing at New York, in the county of New York and State of New York, have invented certain new and useful Improvements in Educational Games, of which the following is a specification.

My invention relates to games and to an appliance for playing the same.

My object is to provide a game board adapted to the playing of a number of interesting games designed to afford amusement and instruction to both children and older persons.

Another object is to provide a device of this kind which will have an intrinsic value within itself as an educational appliance in the home.

Another important object is to provide a game which employs, as a part of the very warp and woof of the game, certain symbols and certain information which it is desired to impress upon the mind of the players.

A further object is to provide a device of this character, which will be neat and attractive in appearance, and durable in construction.

The invention consists in certain novel features which will be hereinafter described and claimed; reference being had to the accompanying drawings, which illustrate my game board, as employed for playing one of the simplest games with which it is used.

In the drawing, Figure 1 is a top plan view of my game board, and Fig. 2 is a central section thereof.

The board in the form here illustrated is designed to familiarize children with the letters of the alphabet, and with the first five numerals.

The numeral 1 indicates the board which is formed of any suitable material, and is preferably square. It is provided with a circular field bounded by the circle 2. This circular field is further divided into concentric rings or zones by the circles 3, 4, 5, and 6, all of said circles being equidistant from each other. The zones, beginning at the circumference of this circular field, are indicated by the numerals 7, 8, 9, and 10, respectively; and the portion at the center of the board inclosed by the ring 6, is indicated by the numeral 11.

The circular field is divided into two equal parts by the heavy horizontally disposed diametrical line A, and each of these parts is divided into thirteen equal parts ⁶⁰ _b by the radial lines *a* which extend from the line 2 to the line 6; thus dividing the circular field of the board into twenty-six equal radial parts corresponding to the twenty-six letters of the English alphabet, ⁶⁵ which letters are placed just outside the circle 2, opposite the outer ends of said twenty-six radial spaces.

The letter A is opposite the outer end of the upper radial section at the left side ⁷⁰ of the lower half of the circular field, and the letters read around from left to right, so that the radial parts or segments forming the lower half of the circular field, have opposite them the letters of the alphabet from A to M inclusive, while the upper part of the field has the letters N to Z inclusive.

The board illustrated in the drawings is arranged for two players—one to be seated ⁸⁰ at the lower side of the board and the other at the upper side, each player using the part of the board on his side of the heavy diametrical line A. Seated in this way, it will be seen that the letters at each player's side of the board will be right side up to him.

While each radial portion *b* of the circular field has a letter of the alphabet at its outer end, it has also a numeral at its inner ⁹⁰ end; and these numerals are likewise so arranged that each player's numerals appear right side up to him. The middle radial section of each half of the circular field has at its inner end the numeral 1; and the ⁹⁵ numerals are so arranged at each side of the board that they read 1, 2, 3, 4, 5, 1, 2, whether read forward or backward. That is to say; they read up to 5 and then they begin to repeat; because in the present ¹⁰⁰ instance it is only desired to deal with the first five numerals, in order to teach children the form of these numerals, and to encourage them to begin to count, up to that number.

A different arrangement of numerals could be adopted, without in the least changing the way of playing the game, if it were desired to make the change,—as, for instance, they could begin with 1 placed opposite the letter A, and go around to 26 opposite Z, which would associate each letter

105

110

with the figure or figures indicating its proper numerical order in the alphabet. Or the small letters of the alphabet might take the place of the numerals at the inner ends of the radial segments. Of course, the letters of the alphabet which appear on the drawings might be placed on the radial segments instead of just opposite their outer ends.

10 At the center of the board and slightly above the face thereof I provide an arrow 12 which is mounted to loosely rotate on a pivot 13 at the center of the board, the pivot having at its lower end a threaded portion 14 for conveniently and firmly engaging the board.

15 In connection with my board I employ the playing blocks or disks 15, of which I provide any desired number, but preferably (in the present instance), thirteen for each half of the board; to correspond to the whole number of radial segments *b*, or to the twenty-six letters of the alphabet which appear around the circumference of the circular field.

20 In playing the game, each player takes turn about in giving the arrow 12 a whirl; and where the arrow points when it comes to rest, is the place where a play must be made. When the arrow has been given a whirl and stops in the position indicated in Fig. 1, the party who sits at the upper side of the board has the play because the arrow points to one of the radial segments on his 25 side of the board. He says "4W," and takes one of the disks 15 and places it in the first or outer zone 7 of the segment 4W: then the arrow is given another whirl by the opposite party from the one who whirled it before, and if it stops again in the same position as before, the player at the upper side of the board again says "4W" and moves his disk 30 from zone 7 to zone 8 (toward the center of the board) in the segment 4W, etc.

35 The object of the player is to get all his disks across all four of the zones into the space 11 at the center of the board where the arrow is. When a disk crosses the line 6 from the zone 10 into 11, it is home; and the 40 player who gets all his disks or "men" home first, has won the game. As soon as a disk has reached home in the central space 11, it can be removed from the board and laid aside so as to give a clear field for the arrow to whirl in. But one of the most amus-

45 ing parts of the game is when the arrow, after being whirled by one of the players, comes to rest pointing at one of the radial lines *a*; for then, any disk 15 which happens 50 to be in either of the radial segments *b* on either side of that line, must be moved backward (outward) one zone. That is to say; suppose the arrow stops in the position indicated in dotted lines in Fig. 1: and let us 55 further suppose that the player seated at

the upper end of the board has two of his disks in the position indicated by dotted lines; namely, one disk in zone 9 of 2S, and one in zone 8 of 3R; then he will have to move each one of these disks outward (backward) one zone: that is, the disk in the segment 2S of zone 9 will have to be moved to 2S zone 8, and the one in 3R of zone 8 will have to be moved backward to 3R of zone 7. When the arrow comes to rest in the position indicated in dotted lines, it gives the player at the lower side of the board great amusement when his opponent has to announce "3, 2, R, S," and move his disks in those segments backward.

60 The number of persons who may engage in playing a game with my device is not at all limited to two. Twenty-six persons could all play the game at one time if desired, by each person taking one segment opposite a given letter of the alphabet. If one of a group of players takes two or three letters (say the initials of his name), and plays on the segments opposite those letters only, he will have just as good a chance to win the 65 game as the fellow who is playing on twice or three times as many letters, because that fellow will have to land twice or three times as many disks inside the inner circle in order to win the game. Hence it may be left optional with a player as to how many letters (or segments) he will take in a game.

66 For each player to play on one segment only, simplifies the game very much for little children, and enables a large number of them to play the game at one time, which is often desirable, as children generally enjoy playing in large groups. Playing the game in this way the close attention of all the children is held, since each one eagerly awaits 70 his turn to whirl the arrow; and then each one almost holds his breath to see if it will not stop opposite his segment, or possibly opposite a radial line.

75 I will now describe another very interesting way for children to play a game on this board, the object of this method being two-fold, as follows: First,—in addition to familiarizing them with the letters of the alphabet, to teach them to count readily and accurately up to five, and to quickly recognize the first five figures or digits when they see them. Secondly:—to make the game proceed sufficiently fast to prevent them from becoming weary.

80 It has already been pointed out that the circular field of the board is divided into five zones indicated on the drawings by the numerals 7, 8, 9, 10, and 11; and that the first five figures or digits—1, 2, 3, 4, and 5, are 85 used at the inner ends of the segments *b* surrounding the arrow. Now, these five figures have direct reference to the zones on the board which are also five in number.

86 Let us suppose that the children are play-

ing the game in the way we are now considering; and that the arrow is pointing at 4, as indicated in Fig. 1 of the drawings: then the player at the upper side of the board will say "W4"—the W indicating the segment he is to play on; and the 4 indicating the number of the zone he is entitled to move to. Hence he will place one of the disks 15 on the outer zone 7 of the segment W, and move it down the segment toward the center of the board. As he lays the disk on the outer end of the segment in the first zone, he says, "one"; and as he moves it into the next zone (8) he says, "two"; and so on, till he has moved it toward the center four zones, or to zone 10. Then let us suppose that the arrow after having been whirled again, stops next time at 3 in the segment V. That position of the arrow will permit the player at the upper side of the board to place a disk on the letter V and move it down the segment V toward the center of the circular field, three zones which will be to zone 9. But if he prefers, he can, instead of that, move the disk that is now on zone 10 of segment W, from zone 10 to zone 11, which will put that disk home, and still leave two moves coming to him, which will permit him to move the disk on the segment V across zone 7 into zone 8. In playing the game that way, the child has to subtract the one move (made on the segment W) from the three moves due him on the segment V: and thus he begins to learn subtraction.

If in playing the game as just indicated, the arrow stops at "5", that permits the player at that side of the board to move a disk clear home to the zone 11 at one move. Hence, it will be seen that, playing the game in this way, makes it go fast enough and easy enough to please small children.

It is purely optional as to how many segments my circular field may be divided into: that is determined by the number of objects it is desired to impress upon the mind of the players.

The letters of the alphabet at the outer ends of the segments b, are inclosed by the angles 16, which form a series of points around the circular field.

The names or the photographs of public characters, as for instance, the Presidents of the United States, may take the place of the letters of the alphabet on my board, till the players have become thoroughly familiar with their names and the order of their election. Likewise, again, the names of different States of the United States may take the place of the letters of the alphabet: or the names of the chief cities of the country: or the names of the capitals of the States, or of the great countries of the world. The segments and zones may be filled with the pictures of great public buildings with very brief descriptions thereof: or with the names

and dates of great national events; or of national holidays, as July 4; Feby. 22; May 30; Dec. 25; etc.

Suppose it is desirable to familiarize a child with the leaders, localities, etc., that became conspicuous in the Civil War: then we may have a very interesting war game, by substituting for the letters of the alphabet, the names of those persons and places, and things; or some suitable photograph of them. On one side of the circular field of the board could appear the names of Lincoln, Stanton, Grant, Sherman, Sheridan, Washington city, Gettysburg, etc. On the other half would appear Davis, Benjamin, Lee, Jackson, Stuart, Richmond, Atlanta, etc. On one side of the board could be a picture of the Monitor, and on the other side a picture of the Merrimac. On one side, in the corner or elsewhere, could appear the stars and stripes, and on the other side the stars and bars of the Confederacy.

From the foregoing, it will be seen that my game board may be made the means of imparting to the players a vast amount of valuable information in most any field of knowledge desired; and may be made a valuable factor in the education of children.

Having thus described my invention, and pointed out its general principles; and having specifically illustrated and described one form thereof; what I claim as new and desire to secure by Letters Patent is:—

1. In a device of the character described, a board provided with a circular field having a central circle and a plurality of concentric circles between said central circle and the margin of the circular field to divide said field into a series of zones; a series of radial lines intersecting said circles and dividing that part of the circular field into a series of radial segments; game pieces designed to be moved to different zones in said segments identifying characters on the segments indicating the names of the different segments, and the zone within each segment to which the gamepiece is to be moved when a play is to be made on that segment; and a rotatable indicator mounted at the center of the board, adapted to be twirled to indicate the segments upon which the successive plays are to be made.

2. In a device of the character described, a board provided with a circular field having a plurality of concentric circles spaced an equal distance from each other to form said circular field into a series of zones; a series of radial lines equidistant from each other intersecting said circles and dividing the circular field into a series of radial segments; the number of said lines and segments being an even number, whereby to cause each radial line to be in alinement with another radial line at the opposite side of the center of the circular field; a heavy dia-

- metrical line coincident with two of said radial lines dividing said field into two equal parts; game pieces designed to be moved to different zones on said segments; identifying 5 characters on the segments indicating the names of the different segments and the zone within each segment to which the game piece is to be moved when a play is to be made on that segment and a rotatable indicator mounted at the center of said circular field, adapted 10 to be twirled to indicate the segments upon which the successive plays are to be made.
3. A game board provided with a circular field having a plurality of concentric circles spaced an equal distance from each other, to form said field into a series of zones; a diametrical line dividing said circular field into two equal parts; a series of radial lines equidistant from each other, said radial lines intersecting said circles and dividing the circular field into a series of equal radial segments; a letter of the alphabet at the outer end and a numeral at the inner end of each 20 segment; and a rotatable indicator mounted at the center of said circular field.
4. In a device of the character described, a board provided with a circular field having a central circle and a plurality of concentric circles between said central circle and the margin of the circular field to divide said portion of the circular field into a series of zones; a series of radial lines intersecting said circles and dividing that portion of the 30 circular field into a series of radial segments; numerical symbols on said segments, there being as many different symbols employed as there are zones surrounding said central circle, each symbol designating one of said zones; game pieces employed with said board and designed to be moved on said segments to the zones indicated by the respective numerals on the segments; and a rotatable indicator mounted at the center of said circular field and designed to be twirled by the players to cause the indicator to stop opposite different ones of said segments to indicate where each play is to be made.
5. In a device of the character described, a board provided with a circular field having a central circle and a plurality of concentric circles between said central circle and the margin of the circular field to divide said portion of the circular field into a series of zones; a series of radial lines intersecting said circles and dividing that portion of the circular field into a series of radial segments;
- identifying numerals at the inner ends of said segments, the numerals employed beginning with a given numeral designating the outer zone and increasing consecutively till as many different numerals have been employed as there are zones surrounding the central circle, a rotatable indicator mounted at the center of said circular field, and designed to be twirled by the players before each play, to cause the indicator to stop opposite different ones of said segments, to thus indicate the segment upon which each play is to be made; and game pieces employed with said board and designed to be moved on said segments, from the margin of the circular field toward the center thereof as many zones as indicated by the relative value of the numeral on the segment at which the arrow points when it stops after being twirled.
6. In a device of the character described, a board provided with a circular field having a central circle and a plurality of concentric circles between said central circle and the margin of the circular field to divide said portion of the circular field into a series of zones; a series of radial lines intersecting said circles and dividing that portion of the circular field into a series of radial segments; numerical symbols at the inner ends of said segments, there being as many different symbols employed as there are zones surrounding the central circle, said symbols beginning with "1" which is employed to designate the outer zone and increasing consecutively, each succeeding numeral indicating one more than the numeral preceding it, a rotatable indicator mounted at the center of said circular field, and designed to be twirled by the players before each play, to cause the indicator to stop opposite different ones of said segments, to thus indicate the segment upon which each play is to be made; and game pieces employed with said board and designed to be moved on said segments, from the margin of the circular field toward the center thereof, as many zones as indicated by the value of the numeral on the segment at which the arrow points when it stops after being twirled.

In testimony whereof I affix my signature in the presence of two witnesses.
